CORE LIFTER

Frank Miller, East Orange, N. J., assignor to
 Ingersoll-Rand Company, Jersey City, N. J.,
 a corporation of New Jersey

Application December 1, 1938, Serial No. 243,361

6 Claims. (Cl. 255—72)

This invention relates to lifting devices, and more particularly to a core lifter adapted to lift a core from the drill hole.

One object of the invention is to facilitate the operations of attaching the core lifter to and releasing it from the core.

Other objects will be in part obvious and in part pointed out hereinafter.

In the drawing accompanying this specification and in which similar reference numerals refer to similar parts:

Figure 1 is an elevation, partly in section, of a core lifter constructed in accordance with the practice of the invention and showing the position which the parts are required to assume to receive the core;

Figure 2 is a similar view showing the relative positions of the parts for gripping the core, and

Figure 3 is a transverse view taken through Figure 1 on the line 3—3.

Referring more particularly to the drawing, 20 designates, in general, the core lifter and 21 a core defined by an annular kerf 22 in a bed of rock 23.

The core lifter, constructed in accordance with the practice of the invention, comprises an outer casing 24 and a sleeve 25 arranged within the casing 24. Both the casing and the sleeve are of cup-shape and the portion of the sleeve adjacent its open end has longitudinally extending slots 26 to form flexible fingers 27 having serrations 28 on their inner surfaces for gripping the core 21.

The peripheral portions of the fingers 27 in the transverse plane of the serrations have inclined surfaces 29 which cooperate with a coniform surface 30 in the front end of the casing 24 to flex the fingers 27 inwardly and thereby cause the serrations 28 to be pressed into the surface of the core 21.

Suitable means are provided for conveniently effecting relative longitudinal movement between the casing 24 to slide the coniform surface 30 over the inclined surfaces 29 for contracting the sleeve. To this end the bottom or end wall 31 of the sleeve is provided, on its outer surface, with a bracket 32 which extends through an aperture 33 in the end wall 34 of the casing 24. The aperture 33 and the portion of the bracket 32 lying therein may be of rectangular or other suitable shape to prevent relative rotary movement between the casing and the sleeve and the bracket has a pair of arms 35 that are suitably spaced with respect to each other to accommodate there-

between a sheave 36 which is mounted upon a pin 37 seated in the arms 35.

In the upper ends of the arms 35 is a draw-pin 38 which also extends through an end of a link 39 having an aperture 40 in its opposite end 5 to receive a hook 41 on a cable 42 which may lead from suitable hoisting mechanism (not shown).

The link 39 also carries a sheave 43 mounted upon a pin 44 seated in the link, and on the outer surface of the wall 34, diametrically opposite each other and in the same transverse plane as the sheave 36, are bearings 45 which may be secured to the wall 34 in any suitable manner. In the bearings 45 are shafts 46 for sheaves 47 15 which are positioned at a lower elevation than the sheave 36, and trained over the upper sides of the sheaves 43 and 36 and around the undersides of the sheaves 47 is an endless flexible member 49 for transmitting the power required 20 to effect the relative movement necessary between the casing and the sleeve for contracting the sleeve.

Although the surfaces 30 and 29 are inclined in such degree as to enable the casing 24 to drop by gravity after the core has been lifted to the surface and the lifting force has been released, it is found that this free descending movement of the casing is sometimes hampered by dirt present on the surfaces 30 and 29 and that the casing 24 must, therefore, be shifted forcibly with respect to the sleeve to bring these elements into positions in which the fingers 27 may again swing outwardly to release the core. The sleeve 25 is accordingly provided with a series of screws 48 secured to the wall 31 and extending through the wall 34. The screws 48 are of suitable length to make possible the necessary adjustments between the casing and the sleeve and carry nuts 49 which act against the outer surface of the wall 34 for that purpose. 40

In practice, whenever it is intended to remove a core the core lifter is lowered into the kerf 22 until the wall 31 seats against the upper end of the core. The parts will be in position to receive the core since, during the operation of lowering the core lifter, the draw-pin 38 will be in position to connect the link 39 with the arms 35 and the casing 24 will merely seat upon the upper end of the sleeve 25. In this arrangement of the parts the sleeve will be fully retracted in the casing and the fingers 27 will assume their normal positions so that the core 21 may readily enter the sleeve. 50

After the core lifter has been positioned cor- 55

rectly on the core the draw-pin 38 is removed to disconnect the link 39 from the arms 35 and lifting force is next applied to the link 39 through the cable 42. During the initial lifting movement of the cable 42 the flexible member 19 is drawn taut and tends to press the sleeve downwardly and will raise the casing 24 relatively to the sleeve. This movement of the casing will draw the conformal surface 30 over the inclined surfaces 29 and cause the fingers 27 to be pressed inwardly and the serrations 28 to be pressed into the surface of the core.

The core lifter, together with the core, may then be raised to the surface of the ground and seated with its lowermost end upon a suitable object or support raised somewhat above the surface of the ground and capable of entering the casing 24. The cable 42 is then released to permit the casing 24 to slide downwardly along the sleeve 25 for releasing the fingers 27. In the event that the frictional engagement between the surfaces 30 and 29 may not be released in this manner the nuts 49 are threaded downwardly on the bolts 48 and in this way the frictional engagement between the surfaces 30 and 29 may be broken.

After the casing has again assumed a position in which its end wall 34 seats against the wall 31 of the sleeve the draw-pin 38 is inserted in the link 39 and the arms 35 and the core lifter will again be in readiness for insertion into the drill hole.

I claim:

1. A core lifter, comprising a contractible sleeve, core gripping means on the sleeve, a casing encircling the sleeve, means on the casing for causing contraction of the sleeve, and means connected to the casing and the sleeve and acting simultaneously against both for moving the casing longitudinally of the sleeve for contracting the sleeve.

2. A core lifter, comprising a contractible sleeve, core gripping means on the sleeve, a casing encircling the sleeve, means on the casing for causing contraction of the skirt, and means connected to the casing and the sleeve and acting against both for moving the sleeve and the casing simultaneously in opposite directions to contract the sleeve.

3. A core lifter, comprising a contractible sleeve, core gripping means on the sleeve, a casing encircling the sleeve, means on the casing for causing contraction of the casing, means for preventing relative rotary movement between the casing and the sleeve, and means connected to the casing and the sleeve for simultaneously moving the casing and the sleeve longitudinally of each other in opposite directions for contracting the sleeve.

4. A core lifter comprising a contractible sleeve, core gripping means on the sleeve, a casing encircling the sleeve, means on the casing for causing contraction of the casing, means for preventing relative rotary movement between the casing and the sleeve, end walls on corresponding ends of the casing and the sleeve, and means connected to and acting against the end walls for simultaneously moving the casing and the sleeve longitudinally of each other in opposite directions for contracting the sleeve.

5. A core lifter, comprising a contractible sleeve, core gripping means on the sleeve, a casing encircling the sleeve, means on the casing for causing contraction of the sleeve, sheaves on corresponding ends of the sleeve and the casing, a flexible member trained over the sheaves for pulling the casing longitudinally of the sleeve in one direction to contract the sleeve, and means for effecting longitudinal movement of the casing in the opposite direction with respect to the sleeve to permit expansion of the sleeve.

6. A core lifter, comprising a contractible sleeve, core gripping means on the sleeve, a casing encircling the sleeve, means on the casing for causing contraction of the sleeve, a pair of sheaves on the casing, a sheave on the sleeve disposed between and above said sheaves, a flexible member trained over the top of the sheave on the sleeve and around the underside of the first mentioned sheaves for pulling the casing longitudinally of the sleeve in one direction to contract the sleeve, screws on the sleeve, and nuts on the screws acting against the casing for effecting longitudinal movement of the casing in the opposite direction with respect to the sleeve to permit expansion of the sleeve.

FRANK MILLER.
